US00D505460S

(12) **United States Design Patent** (10) Patent No.: **US D505,460 S**
 Dalebout et al. (45) Date of Patent: **** May 24, 2005**

(54) **EXERCISE DEVICE**

(75) Inventors: **William T. Dalebout**, N. Logan, UT (US); **Richard Eldon Fry**, Provo, UT (US); **Adrianus G. Van Dam**, Hyde Park, UT (US)

(73) Assignee: **Reebok International Ltd.**, Canton, MA (US)

(**) Term: **14 Years**

(21) Appl. No.: **29/186,005**

(22) Filed: **Jul. 9, 2003**

Related U.S. Application Data

(62) Division of application No. 09/737,392, filed on Dec. 15, 2000.

(51) LOC (7) Cl. **21-02**

(52) U.S. Cl. **D21/688; D21/689; D21/671**

(58) Field of Search **D21/662, 671, D21/688, 689, 692; 482/123, 146, 147**

Primary Examiner—Philip S. Hyder*(74) Attorney, Agent, or Firm*—Sterne, Kessler, Goldstein & Fox, PLLC(57) **CLAIM**

The ornamental design for an exercise device, as shown and described.

DESCRIPTION

FIG. 1 is a front view of an exercise device showing a new design;

FIG. 2 is a perspective view of the base of the exercise device in FIG. 1; and,

FIG. 3 is a top perspective view of a top surface of the exercise device of FIG. 1.

The even broken lines showing a person and portions of an exercise device are environmental only and form no part of the claimed design.
